UNITED STATES PATENT OFFICE.

JAMES A. WEST, OF BELLWOOD, NEBRASKA.

ATTACHMENT FOR PAPER-STANDS.

1,205,827.

Specification of Letters Patent. Patented Nov. 21, 1916.

Application filed February 7, 1916. Serial No. 76,830.

To all whom it may concern:

Be it known that I, JAMES A. WEST, a citizen of the United States, residing at Bellwood, in the county of Butler and State of Nebraska, have invented new and useful 5 Improvements in Attachments for Paper-Stands, of which the following is a specification.

This invention relates to an attachment 10 for paper stands and more particularly to that type of stand upon which is supported a roll of wrapping paper and provided with a spring pressed tearing bar.

The primary object of the invention is to 15 provide a device engageable with the tearing bar and having an arm so arranged that the finger on said arm is positioned beneath the tearing bar and the free end of the strip of paper on the roll to hold said free end 20 in spaced relation with the roll to enable said free end to be readily grasped to unwind a portion of the strip from the roll and to tear the same by means of the tearing bar.

Another object of the invention is to provide 25 the device with an arm positioned beneath the tearing bar and curved in such a manner that when the roll is moved to cause the free end thereof to extend below the 30 tearing bar, said arm will guide the free end of the roll away from the roll and prevent said end from adhering to the roll, thus enabling the same to be easily grasped 35 between the thumb and forefinger to further unwind a portion of the roll.

Another object of the invention is to provide 40 a device with clamping jaws and means for securing the jaws to the tearing bar on the frame which will permit the device to be used upon stands having tearing bars of 45 different sizes.

A still further object of the invention is to provide one of the clamping jaws on the device with a member for contact with the 50 end of the roll, whereby the separating finger on the spacing arm may be spaced the required distance from the end of the roll to insure the free end of the roll being held by the spacing arm in spaced relation with the roll.

With these and other objects in view, the invention resides in the novel combination and arrangement of parts which will be hereinafter described and particularly pointed out in the claims.

The preferred embodiment of the inven-

tion has been illustrated in the accompanying drawing, although no restriction is made to the precise details of construction therein shown, as changes, alterations and modifications within the scope of the claims may be resorted to when desired.

In the drawing,—Figure 1 is a front elevation of a paper stand showing the attachment connected to the spring pressed tearing bar on the stand with the free end of the roll positioned slightly below the tearing bar. Fig. 2 is a sectional view through the tearing bar and a portion of the roll, and showing the free end of the roll held 65 in spaced relation with the body of the roll by means of the spacing arm. Fig. 3 is an end elevation of a portion of Fig. 1. Fig. 4 is a detail perspective view of the attachment removed from the tearing bar. Fig. 70 5 is a top plan view of the attachment removed from the tearing bar.

Like characters of reference denote corresponding parts throughout the several views.

Referring now to the drawing in detail, 75 the numeral 1 designates a paper stand which is of the usual construction and comprising spaced supports 2 held in spaced relation by a cross bar 3 and supporting between their ends for turning movement a 80 roll holder 4 upon which is mounted a roll of wrapping paper 5. Secured to the cross piece 3 of the frame is the usual spring pressed tearing bar 6 which contacts with the peripheral edge of the roll at its free 85 end throughout its entire width. As this construction is embodied in paper stands now in common use, further description of the same is deemed unnecessary.

The attachment, which is designated in 90 the drawing by the numeral 7, comprises a body 8 having arranged at one end thereof clamping jaws 9 and 10 and at its opposite end a spacing arm 11 terminating at one end in a separating finger 12, said attachment 95 being preferably formed of sheet metal.

The clamping arm 9 is formed integral with the body 8 which is offset at the junction of said body with the arm to position the arm in advance of the body and provide a stop shoulder 13 against which the bottom edge of the tearing bar 6 is adapted to contact when the arm 9 is positioned thereon. Both of the jaws 9 and 10 are provided at their lower ends with an opening 14 and at their upper ends with an elongated and longitudinally extending slot 15,

- said slots and openings being adapted to register and receive fastening elements 16 by means of which the clamping jaws may be frictionally engaged with the opposite side of the tearing bar 6, while the elongated slots 15 allow vertical adjustment of one of the fastening elements 15, so that tearing bars varying in height may be accommodated between the clamping jaws.
- 10 The clamping jaw 10 has projecting laterally from one side thereof and between its ends a spacing member 17 bent between its ends, as at 18, to provide a stop shoulder 19 for contact with one end of a roll to insure the proper spacing from the end of the roll of the spacing arm 11 and separating finger 12, said spacing member overlying in spaced relation the body 8 of the attachment and with the stop shoulder 19 extending beyond 20 and at right angles to the body 8. The upper end of the stop shoulder 19 is curved toward the clamping jaws 9 and 10, as indicated by the numeral 20.
- The separating finger 12 is provided with 25 oppositely inclined sides 21 which converge at a point a short distance above the upper edge of the body 8, while the spacing arm 11 is curved outwardly and away from the body 8 throughout its entire length.
- 30 When it is desired to use the attachment in connection with a paper stand for spacing the free end of the roll from the body thereof, the fastening elements 16 which connect the clamping jaws 9 and 10 are loosened to enable one end of the tearing bar 6 to be positioned therebetween. The attachment is now passed along the bar until the stop shoulder 19 contacts with the end of the roll, and with the attachment in this position, the fastening 35 elements are adjusted to frictionally clamp a portion of the tearing bar 6 between the clamping jaws. The roll holder is now rotated to cause the separating finger 12 to pass between the free edge of the roll and the body thereof, and it will be noted with reference to Fig. 1 of the drawing that the stop shoulder 13 limits the distance that the separating finger 12 extends beneath the tearing bar 6, and also enables the body 8 to 40 contact with the peripheral surface of the roll below the free edge for the entire length of the body, so that when the operator places his hand upon the roll to turn the same to cause the free edge of the paper to pass below the bottom edge of the tearing bar, said free edge will be guided by the curved spacing arm and body 8 away from the roll and will be held in this position by the spacing arm to enable the person using the paper to 45 grasp the free edge thereof between the thumb and forefinger, and by exerting a pull thereon cause the roll to rotate until sufficient paper has been withdrawn from

beneath the tearing bar to accommodate the article to be wrapped. 65

From the foregoing description, taken in connection with the drawing, it is at once apparent that an attachment for paper stands has been provided for the purpose set forth which is simple in construction, inexpensive of manufacture and highly efficient in use. 70

Having thus described the invention, what is claimed as new is:—

1. The combination with a paper stand 75 having a roll of wrapping paper mounted thereon and a spring pressed tearing bar, of an attachment for said bar comprising a body, a downwardly extending spacing arm at one end of the body and curved outwardly 80 therefrom throughout its length, a separating finger on said arm above the body adapted to extend beneath the tearing bar and the free edge of the paper roll, a clamping jaw formed integral with the other end 85 of the body and extending above the same, a second clamping jaw, means for adjustably connecting said jaws with the tearing bar, and a spacing member formed integral with the last mentioned jaw and between the ends 90 thereof.

2. The combination with a paper stand having a roll of paper mounted thereon and a spring pressed tearing bar, of an attachment 95 for said bar comprising a body, a spacing arm at one end of the body curved throughout its length, a separating finger formed integral with said arm to extend above said body, an upwardly extending clamping jaw at the opposite end of the 100 body, a second clamping jaw, fastening elements passing through said jaws and adapted to removably connect the same with the tearing bar, a spacing member formed integral with the last mentioned jaw, and a 105 stop shoulder formed from said member and adapted to contact with the end of the roll of paper to space the separating finger and the spacing arm a predetermined distance from the end of said roll. 110

3. A device of the class described comprising a body, a spacing arm at one end of the body and extending below the same, a separating finger formed integral with the spacing arm and extending above said body, 115 spaced clamping jaws, one of which is formed integral with the body and each provided with an alined slot, and fastening elements passing through said jaws with one of said elements movable in said slots. 120

In testimony whereof I affix my signature in presence of two witnesses.

JAMES A. WEST.
